(57) **CLAIM**

The ornamental design for an adapter for charging, as shown and described.

DESCRIPTION

FIG. 1 is a left front perspective view of an adapter for charging, showing our new design;
FIG. 2 is a right front bottom perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a right side elevational view thereof;
FIG. 8 is a left side elevational view thereof;
FIG. 9 is a left front perspective view thereof, showing the connector and cable portion in the undocked state;
FIG. 10 is a left side elevational view thereof, showing the connector and cable portion in the undocked state; and,
FIG. 11 is a perspective view showing the adapter for charging in use.
The broken lines illustrate environmental structure and form no part of the claimed design.
